PORABLE LANTERN

Edward J. Garland, Shrewsbury, Mass.

Application January 7, 1954, Serial No. 28,400

Term of patent 14 years

(Cl. D48—24)

To all whom it may concern:

Be it known that I, Edward J. Garland, a citizen of the United States, residing at Shrewsbury, Worcester County, Massachusetts, have invented a new, original, and ornamental Design for a Portable Lantern, of which the following is a specification, reference being had to the accompanying drawing, forming a part thereof.

Figure 1 is a side perspective view of a portable lantern, showing my new design.

Figure 2 is a top plan view thereof; and

Figure 3 is a rear end elevational view.

I claim:

The ornamental design for a portable lantern, as shown.
